US0D1032547S

(12) **United States Design Patent** (10) **Patent No.:** **US D1,032,547 S**
(45) **Date of Patent:** **** Jun. 25, 2024**

(54) **ELECTRIC ACTUATOR**

(71) Applicant: **Sonceboz Mechatronics Boncourt**,
Boncourt (CH)

(72) Inventor: **Guillaume Loussert**, Boncourt (CH)

(73) Assignee: **Sonceboz Mechatronics Boncourt**,
Boncourt (CH)

(**) Term: **15 Years**

(21) Appl. No.: **29/759,503**

(22) Filed: **Nov. 23, 2020**

Related U.S. Application Data

(62) Division of application No. 35/507,940, filed on Feb. 20, 2019 (U.S. filing date under 35 U.S.C. 384), and having an international filing date of Feb. 20, 2019, now abandoned.

(57) **CLAIM**

The ornamental design for an electric actuator, as shown and described.

DESCRIPTION

FIG. 1 is a top, rear left perspective view of the design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is another perspective view thereof; and,

FIG. 10 is another perspective view thereof.

The broken lines in FIGS. 1-10 illustrate portions of the electric actuator that form no part of the claimed design.

1 Claim, 10 Drawing Sheets
